Primary Examiner—James Gandy**Assistant Examiner**—Cathron B. Matta**Attorney, Agent, or Firm**—Richard B. O'Planick[57] **CLAIM**

The ornamental design for a bottle top, as shown and described.

DESCRIPTION

FIG. 1 a top right front perspective view of a bottle top showing my new design;

FIG. 2 is a top plan view thereof;

FIG. 3 is a front elevational view thereof;

FIG. 4 is a right side elevational view thereof; the left side elevational view being a mirror image; and,

FIG. 5 is a rear elevational view thereof.

The bottom and interior of the bottle top form no part of the claimed design. The broken line showing in FIG. 5 of interior portions of the cap, and the broken line showing on the exterior surfaces of the cap, are for illustrative purposes only and form no part of the claimed design.
